UNITED STATES PATENT OFFICE.

ALP J. RODMAN, OF RADNOR, OHIO.

BURIAL-VAULT.

1,183,034.

Specification of Letters Patent.

Patented May 16, 1916.

Application filed February 27, 1915. Serial No. 10,924.

To all whom it may concern:

Be it known that I, ALP J. RODMAN, a citizen of the United States of America, residing at Radnor, in the county of Delaware and State of Ohio, have invented certain new and useful Improvements in Burial-Vaults, of which the following is a specification.

My invention relates to burial vaults, and 10 has for its object to provide a vault composed of a plurality of portable sections and so constructed that the sections when assembled together form a strong and durable vault structure adapted to form a permanent receptacle for a burial casket.

In the accompanying drawing wherein like reference numerals indicate like parts throughout the several figures, Figure 1 is a side elevation of a vault constructing according to my invention, the cover being in place. Fig. 2 is a top plan view showing a portion of the cover in place. Fig. 3 is an end view of the vault with cover in place. Fig. 4 is a transverse sectional view on the 25 line 4—4 Fig. 2.

Referring more specifically to the drawings the numeral 1 designates my burial vault as a whole constructed of the bottom slabs 2, the combined end and side sections 3 and the cover or top 4 all of which parts are of any well known artificial stone preparation. The abutting edges of the bottom slabs 2 are provided with interfitting V-shaped beveled edges and V-shaped 35 grooves 5 and 6 respectively. A suitable cementitious material 7 is placed within the grooves 6 before the slabs are placed in position for an obvious purpose.

The combined end and side sections are in 40 the form of right angles one leg of the right angle comprising a portion of the end wall of the vault while the other leg forms part of the side wall thereof. These angular sections have their bottom edges cemented to 45 the bottom wall of the vault formed by the slabs 2 as at 8 while the top edges of the sections are provided with V-shaped grooves 9 adapted to receive the beveled bottom edges 10 of a second tier of sections 12. The 50 grooves 9 like the grooves 6 are filled with cement 11 before the sections are assembled. The sections are so constructed and laid that the joints formed by the meeting edges of one tier of sections do not coincide with the

joints in the adjacent section as best illustrated in Figs. 1, 3, and 4. In other words, each right angled slab is formed with a long leg and a short one which are set up as shown in Figs. 3 and 4, the short legs of one tier of slabs being superposed on the 60 long legs of those slabs composing the tier beneath so that the joints thus formed will be staggered. Preferably but two tiers of combined side and end sections are employed but the number may readily be 65 varied to suit requirements.

The top 4 is preferably made of a single slab molded to any desired shape but it is obvious that the top may be made up of interfitting sections similar to those forming 70 the bottom of the vault.

Reinforcing wires 13 embedded in the various sections greatly add to the strength and durability of the vault. Particular attention is drawn to the manner in which 75 portions of the wires 13 embedded in the top or cover 4 are exposed for the purpose of forming handles 14.

From the foregoing it will be seen that my grave vault although constructed of 80 readily transportable and interchangeable parts is as strong and impenetrable as though constructed in the well known way of solid masonry or cement.

Having thus described my invention what 85 I claim is:

In a portable grave vault, a sectional base and cover, sectional walls comprising a plurality of layers made up of L shape members adapted to serve as combined end and 90 side sections, the shank of one L section being longer than that of the abutting section and the longer shank extending past the transverse middle of the vault and the foot of the shorter section extending past the 95 longitudinal middle of the vault, the short shank of one tier of slabs being superposed on the long shank of the slabs beneath so that the joints thus formed will be staggered, and means for securing said elements 100 together.

In testimony whereof I affix my signature in presence of two witnesses.

ALP J. RODMAN.

Witnesses:

BERNE JONES,
LIZZIE RODMAN.
